TREATMENT OF HYDROCARBON OILS

Carbon P. Dubbs, Chicago, Ill., assignor to Universal Oil Products Company, Chicago, Ill., a corporation of South Dakota

Application February 27, 1931, Serial No. 518,617

1 Claim. (Cl. 196—66)

This invention relates to the treatment of hydrocarbon oils and refers more particularly to the production of low boiling point hydrocarbon mixtures, suitable for use as fuel in internal combustion engines, from hydrocarbon mixtures of relatively higher boiling point by the application of heat and pressure, with the production of materially increased yields of hydrocarbons of gasoline boiling point range over that commonly encountered in cracking processes.

More specifically, the invention contemplates the utilization of reactive gas mixtures containing hydrogen in preponderating amounts, produced electrically, the hydrogen and hydrogen-containing gases so produced being utilized to influence the course of the cracking reaction in the general direction of increased yields of compounds of relatively high hydrogen content boiling within the range of gasoline.

20 In a specific embodiment of the invention, a heavy hydrocarbon oil, typified by a crude oil from which compounds of gasoline boiling point range have been removed by ordinary non-cracking distillation methods, may be fed to a heating zone of a cracking unit, either directly or after heat exchange and contact relation with the products of the cracking reaction undergoing treatment in a fractionating zone of said unit; the heated products from said heating zone may 25 be introduced into an enlarged reaction zone for further reaction and wherein an electric arc, resistance unit, or other means may be disposed, adapted to activate the vaporous portions of the products of reaction after their admixture with 30 previously activated gases or gaseous mixtures. The reaction zone products may then be passed to suitable dephlegmating apparatus from whence vapors may issue to cooling, condensing and collecting equipment of the process, and unvaporized dephlegmated portions of said products are 35 returned to the heating zone for further treatment.

Other and further objects and advantages of the invention will become apparent from the following description and accompanying diagrammatic drawing showing a side-elevational view of one form of apparatus in which the invention may be carried out.

Referring to the drawing, raw oil charging 40 stock, such as topped crude, may be passed from a suitable source of supply (not shown) through a line 1, controlled by valve 2, to a pump 3 for discharge into a line 4 leading from said pump. As desired, said raw feed may be passed through 45 a line 5, controlled by valve 6, communicating

with said line 4, and introduced into a fractionator or dephlegmator 26 wherein the products of reaction are undergoing treatment, to bring said raw feed in heat exchange relation with such products, cooling said products and incidentally 60 fractionating certain portions of said feed, and after such heat exchange relation, passing from said fractionator, together with the insufficiently converted, relatively heavy portions of the products of reaction through a line 9, controlled by 65 a valve 10, to a line 7, controlled by a valve 8, also in communication with said line 4 and through which said raw oil feed may be fed directly in event it is desired to by-pass said fractionator 26. The raw oil feed and/or mixture of raw oil feed and reflux condensate from 70 said fractionator may be discharged from said line 7 into a pump 11, from whence they may be passed through a line 12, controlled by valve 13 into a tubular heating element 14 disposed within 75 a suitable furnace 15 of any desired type. Activated gas mixtures, produced in a manner to be hereinafter more fully described, may be introduced into feed line 12 through a line 16, controlled by valve 17. 80

The products to be heated within heating element 14 may be subjected to any desired temperature condition therein, depending on the character of the oil and the ultimate desired product. Such temperature may range from 85 about 850° F., to about 950° F., more or less, while the pressures utilized therein may be of the order of 500 to 3000 pounds per square inch.

After subjection to the desired temperature and pressure within said heating element, the heated 90 oils may be passed from said heating element through a line 18, controlled by valve 19 into an enlarged reaction zone wherein further reactions may occur, and wherein a pressure substantially the same as that employed in 95 heating element 14 may be maintained. I have found that due to the activated state of the gases and gaseous mixtures produced by my process, I am enabled to employ a wide range of pressures and that hydrogenation may be 100 effected within relatively low limits and yet effect the desired reactions to produce the ultimate low boiling point product sought.

In order to further promote, progress and accelerate the reactions occurring within chamber 105 20, there may be disposed therein, preferably at or substantially near the vapor outlet thereof, a suitable activating or energizing means, such as electrodes 21 and 21', or any other desired activating means, between or into which gaseous 110

mixtures from a line 22, controlled by valve 23 (said line 22 being in communication with line 16 heretofore referred to), and/or hydrogen from a line 58, controlled by valve 59, or a mixture of line 58, controlled by valve 59, or a mixture of 5 hydrogen and gaseous mixtures, may be introduced into said chamber, to produce a condition favorable to the interaction of hydrogen or hydrogen-containing gases with the vapors produced by the initial cracking of said raw oil introduced by the initial cracking of said raw oil into said reaction zone. As stated, other activating means may be employed, which may take the form of metal plates suspended within proper spacing in said chamber, having a proper electric potential supplied thereto to produce 10 electric discharges of varying intensity up to and including a continuous arc. These electrodes may preferably be of such metals as tungsten; or, if desired, such activation may be effected by means of heating grids of resistance wires to a suitable 15 degree of incandescence. When such resistance grids comprise tungsten or metals of similar characteristics, there is produced a dissociation of hydrogen molecules resulting in a substantial formation of hydrogen in the atomic or reactive 20 state, approximately equivalent amounts of state, approximately equivalent amounts of atomic hydrogen being adsorbed on the surface of the wires and discharged or repelled into the surrounding vapor space of said chamber.

Heavier, unvaporized liquid residual products 30 may be withdrawn from chamber 20 through a line 60, controlled by valve 61, for passage to storage, or for utilization elsewhere. Vapors may be withdrawn from said chamber through line 24, controlled by valve 25, and introduced into fractionator 26, which may preferably be maintained 35 under a substantially reduced pressure from that maintained within said reaction chamber, which pressure may be of the order of from 100 to 500 pounds per square inch, depending upon the pressure maintained within said reaction chamber, 40 while the temperatures employed therein will be proportionate to the temperatures employed and the pressures utilized within heating element 14 and reaction chamber 20, and will be dependent 45 also upon the amount of raw charging oil which may be fed therethrough. In passing through said fractionator, the vapors will effect heat exchange with the incoming raw charging oil passing therethrough, as previously described, and 50 the lighter, uncondensed portions of said vapors may then be passed from said fractionator through a line 27, controlled by valve 28, to a suitable condenser 29, also maintained under a reduced pressure, either the same or lower than 55 that maintained within said fractionator, as desired. Cooling of the vapors is effected within said condenser, with resultant condensation of the products liquefiable at the temperatures and pressures maintained therein, after which the cooled products may pass 60 through a line 30, controlled by valve 31, into a primary receiver 32, from which the liquefied hydrocarbon mixtures of approximately motor fuel boiling point range may be removed through a line 33, controlled by a valve 34. To control the 65 quality of the vapors issuing from fractionator 26, as well as to further aid in controlling and maintaining a relatively constant temperature within said fractionator, any desired amount of the liquid within said primary receiver 32 approximating motor fuel boiling point, may be 70 withdrawn from said receiver and introduced into said fractionator through a line 36, controlled by valve 37, to a pump 35, and passed from said pump through a line 38, controlled by valve 39 75 into the upper portion of said fractionator.

Incondensable and fixed gases produced in the process and collecting within said primary receiver 32 may be discharged from said receiver 32 through a line 39', controlled by valve 40, to a pump 41 (should the pressure differential entail the necessity of use of said pump), and discharged from said pump through a line 42, controlled by valve 43 into a secondary receiver or activating unit 44; or if it be unnecessary or undesirable to subject such gases to treatment within said unit 44, such gases may be recycled from said line 42 leading to said unit 44, through a line 45, controlled by valve 46, to a pump 47, communicating with line 16 previously referred to, leading to said reaction chamber 20 through communication with line 22 hereinbefore referred to, and wherein such gases may be subjected, as previously described, to the activating action of the electrodes 21 and 21' disposed within said chamber; or, if such activating action be undesirable or unnecessary, such gases may be passed directly from said line 16 to said line 12 through which raw oil and reflux condensate may be passing to heating element 14, as previously described.

In addition to the incondensable gases produced in the process and passed into said chamber 44, extraneous gases, similar in characteristic to such incondensable gases may also be introduced into said chamber through a line 50, controlled by valve 51; or any desired amount 105 of molecular hydrogen (depending upon the extent of hydrogenation to be effected and the hydrogen content of the activated gaseous mixtures produced in said chamber) may be introduced into said chamber, either alone or admixed with 110 extraneous incondensable gases, through a line 53, controlled by valve 52. Any excess of gases or liquid products within said chamber 44 may be withdrawn therefrom through a line 54, controlled by valve 55. The pressures utilized within 115 said chamber may be substantially lower than those employed within said receiver 32 and fractionator 26, and are preferably of the order of about 20 pounds per square inch, or less, or substantially sub-atmospheric.

To produce activated gas mixtures, either alone or admixed with hydrogen or hydrogen-containing gases, the gaseous mixtures introduced into chamber 44 are subjected to activation by means of any typical electrical connections 49 and 49' 125 disposed within said chamber, which means may be substantially similar to those utilized within reaction chamber 20, heretofore described. On subjection to the electrical treatment within said chamber, the molecular hydrogen will be dissociated into reactive forms of either monatomic or triatomic nature, and the excess of hydrogen contained within the incondensable gases will be brought to its activated state. The resultant activated gaseous mixture may then be withdrawn 130 from said chamber through a line 56, controlled by valve 57, to line 45, to pump 47 and thence to line 16 for introduction into reaction chamber 20, or passage with the charging oil being fed to heating element 14, as previously described.

In some instances, the average composition of the gas mixtures to be activated within chamber 44 may approximate that of methane, which is usual when the extraneous gas employed is natural gas. In such event, the passage of the gas 145 mixture through a high temperature electric arc, with pressures in chamber 44 being maintained at points in the neighborhood of 20 millimeters of mercury absolute, there may be produced substantial amounts of acetylene and hydrogen in 150

the approximate volumetric ratio of 1 to 3. This gas mixture may be transmitted by pump 47 to reaction chamber 20, wherein reactions of a character tending toward hydrogenation with increased production of gasoline fractions may be effected. In addition to the reactions of hydrogenation, the reactions between the components of the activated mixture, such as are exemplified by acetylene, tends to produce hydrocarbons of a generally more pronounced aromatic nature. The reactions producing the mixture of acetylene and hydrogen mentioned proceeds at great velocity in an electric arc, but is reversed in succeeding portions of the equipment if immediate cooling is not practiced. In another method of producing similar mixtures, gas mixtures approximating the composition of methane may be heated by external means in chamber 44 to temperatures of the order of about 1750° F., more or less, under pressures of about 10 to 30 millimeters absolute, sufficient space being provided to allow the reaction to progress to completion.

Of course, if desired, a plurality of chambers 44 may be utilized and employed alternately. While certain units may be producing activated hydrogen, in others the resistance wires may be cooled to allow the escape of adsorbed hydrogen and render the wires capable of further dissociation action when reheated again to the proper point of incandescence.

As an example of one operation of the process and results obtainable thereby, a 25 gravity topped crude is fed to the heating element of the process at the rate of approximately 1000 barrels per day. When cracking this stock without the use of activating means within reaction chamber 20 or the introduction of activated gas mixtures,

the overall yield of hydrocarbons approximating gasoline boiling point range may be approximately 60%. The temperature employed in this case at the exit of heating element 14 is about 930° F. and a pressure of about 250 pounds is employed on the reaction chamber. When this charging stock is treated at increased pressures of about 2000 pounds per square inch, and considerable excess of activated hydrogen is employed within the vapor space of the reaction chamber, the yield of hydrocarbons of gasoline boiling point range will be increased to 70% and the quality of the residual oil produced greatly improved as regards carbon content and applicability for processing to produce homogeneous fuel residues and lubricating stocks.

I claim as my invention:—

In a hydrocarbon oil cracking process of the character wherein the oil is heated to cracking temperature under pressure while flowing in a restricted stream through a heating zone and thence discharged into an enlarged unheated reaction zone maintained under cracking conditions of temperature and pressure and wherein vapors are evolved from the heated oil; the improvement which comprises maintaining a region of electrical activation in the vapor space of the reaction zone, subjecting incondensable gases produced in the process to a preliminary activation treatment, then introducing the gases into the reaction zone adjacent the electrical activating region and activating the same therein, reacting the thus activated hydrogen with the oil vapors in the reaction zone, and removing the treated vapors from the reaction zone for fractionating and condensation.
